UNITED STATES PATENT OFFICE.

ARTHUR JUNGHANS, OF SCHRAMBERG, GERMANY.

LUMINOUS SUBSTANCE FOR INDICATORS.

No. 911,401.

Specification of Letters Patent.

Patented Feb. 2, 1909.

Application filed September 27, 1907. Serial No. 394,853.

To all whom it may concern:

Be it known that I, ARTHUR JUNGHANS, royal commercial councilor, a subject of the King of Würtemberg, residing at 5 Schramberg, in the Kingdom of Würtemberg, Germany, have invented certain new and useful improvements relating to improved luminous substance for indicators containing radium for the indicating members of clocks, speed-gages, and the like, of which the following is a full, clear, and exact description.

This invention relates to clocks, speed gages or the like and aims to provide certain improvements therein.

According to the present invention the clock, speed gage or other member is provided with a luminous compound so that it can be read in the dark.

10 The invention includes certain features of construction which render the illumination very effective.

As a luminous compound, I prefer to use a radium salt to which has been added 15 crystalline sulfid of zinc or some other analogous substance.

There is shown by way of example in the accompanying drawing constructional forms of indicating members, such as indicators or pointers and dials in combination with the luminous substance containing radium.

Figure 1 is a dial showing the invention in which the luminous substance is in the 5 form of oval fields or spaces over the figures. Fig. 2 is a dial with the luminous substance in dotted spaces or fields beside the figures. Fig. 3 is a dial, wherein the figures are arranged in fields provided with the luminous substance. Fig. 4 shows a 10 dial wherein the luminous substance is provided in the form of a ring. Fig. 5 shows an indicator or pointer, the whole length of which is provided with the luminous substance. Fig. 6 shows an indicator or pointer with frame-like enlargement, whereon the luminous substance is provided. Figs. 7 and 8 show an indicator or pointer having recesses adapted for the reception of the 15 luminous substance. Figs. 9 and 10 are indicators or pointers, wherein the luminous substance is inserted in a longitudinal aperture or recess of the front part of the indicator.

20 The luminous substance containing radium according to the present invention

may, as shown in the figures of the drawing, be provided either on the dials or on the indicators, or simultaneously on both parts.

The figures of the dials may be located beside or in the fields provided with the luminous substance and in both instances they are readily visible in the dark. As shown in the figures of the drawing, the indicators or pointers may also be provided with the 60 luminous substance in different ways. In the indicator, as shown in Fig. 6, which is provided with a luminous rectangular frame (it may also be round or oval) the figures may be seen through the free opening. The 65 indicator according to Figs. 1 and 9 is formed of two wires *a* and *b* in such a manner that the wires are soldered together at *c* in a point, while they are so soldered with their ends *d* and *e* to the bush *f* that a longitudinal aperture or recess is left for the 70 reception of the luminous substance. The indicator or pointer may also be punched so as to form such longitudinal aperture (Fig. 10) in which case, the luminous substance is 75 preferably attached to material containing collodium.

In any event the luminous substance should be on the outer side of the pointer or indicator. Preferably the substance is 80 present in some considerable bulk where a high illumination is required. In this case the constructions of indicator shown in Figs. 1, 8, 9 and 10 are to be preferred.

What I claim as my invention, and desire to secure by Letters Patent is:

1. In a clock, speed-gage or other similar device an indicator having a recess and a luminous compound in said recess.

2. In a clock, speed-gage or other similar device an indicator formed of two wires 95 fixed together and between them a luminous compound.

3. In a clock, speed-gage or other similar device an indicator having a longitudinal aperture and a luminous compound in 100 said aperture.

4. In a clock, speed-gage or other similar device an indicator having at its outer surface a luminous compound in combination with a dial or the like having its figures or indicating divisions provided with a luminous compound.

5. A clock, speed-gage, or other similar device having a dial provided with a luminous compound in the form of fields or 110 spaces of dotted form located at the figures

of the dial, and having an indicator or pointer constructed of two wires fixed together to form between them a longitudinal aperture or recess, such aperture or recess extending substantially the length of the indicator or pointer, and a luminous compound in said recess extending to the outer surface of the pointer.

In witness whereof, I have hereunto signed my name in the presence of two subscribing witnesses.

ARTHUR JUNGHANS.
